UNITED STATES PATENT OFFICE.

SAMUEL HARRY NORTON, OF MEADVILLE, PENNSYLVANIA.

REAMER.

Application filed July 9, 1924. Serial No. 724,938.

This invention relates to reamers of the adjustable type.

An important object of this invention is to provide a reamer wherein the blades and the pilots associated with the blades may be quickly and conveniently adjusted by the turning of a single collar.

A further object of the invention is to provide a reamer wherein the blades and 10 pilots are connected for adjustment by means of individual leaf springs which not only act as a connecting means for the pilots and blades but also effectively hold the blades and pilots in the grooves in the body 75 of the reamer.

A further object is to produce a reamer which is durable, convenient to adjust and cheap to manufacture.

Other objects and advantages will be apparent during the course of the following description.

In the accompanying drawing forming a part of this application and in which like numerals are employed to designate like 75 parts throughout the same,

Figure 1 is a side elevation of the improved reamer, parts being shown in section;

Figure 2 is an enlarged detailed side elevation of the reamer, parts being shown in section;

Figure 3 is a transverse sectional view taken on the line 3—3 of Figure 2;

Figure 4 is a vertical transverse sectional view taken on line 4—4 of Figure 2;

Figure 5 is a vertical transverse section taken on line 5—5 of Figure 2;

Figure 6 is a perspective of a leaf spring for holding the forward portion of a forward pilot in position;

Figure 7 is a perspective of a leaf spring for connecting a blade and a forward pilot and for holding these parts in position;

Figure 8 is a perspective of one of the 45 springs for connecting the rear pilots to the adjusting collar;

Figure 9 is a fragmentary side elevation of the reamer illustrating the novel form of lead;

Figure 10 is a perspective illustrating a blade embodied in the invention;

Figure 11 is an end elevation illustrating the blades positioned for grinding;

Figure 12 is a transverse sectional view 55 through the reamer illustrating the blades in position for cutting.

In the drawing wherein for the purpose of illustration a preferred embodiment of the invention is shown, the numeral 5 designates a more or less cylindrical body having 60 a series of longitudinally extending grooves 6 which gradually deepen toward the forward portion of the body and which adjustably receive forward pilots 7, blades 8 and rear pilots 9.

In carrying out the invention the blades and the pilots are connected for simultaneous adjustment so that the cutting diameter of the reamer may be varied.

The forward portions of the pilots 7 are 70 formed with notches more or less V-shaped in side elevation to receive the inwardly hooked terminals 10 of retaining springs 11. The forward portions of the retaining springs 11 are provided with laterally extending shoulders 12 which ride over the periphery of the body of the reamer. However, it will be observed that the major portions of the springs 11 are received in the grooves 6 and consequently are held in position thereby. The leaf springs 11 are engaged by a flat endless ring 14 which surrounds the body and which extends into depressions 15 in the intermediate portions of the springs 11. As the endless ring 14 is extended into the depressions 15 sliding of the ring on the springs is positively prevented.

The rear portions of the pilots 7 and the forward portions of the blades 8 are provided with notches 17 and 18 respectively 90 for the reception of the inturned terminal portions 19 of individual leaf springs 20. The major portions of the leaf springs 20 are received in the grooves 6 and are held against lateral movement by the side walls 95 of the grooves. The leaf springs 20 are urged inwardly by an endless ring 21 seated in depressions 23 in the intermediate portions of the individual leaf springs 20. It will be seen that the individual leaf springs 20 not only serve as a means to hold the pilots and the blades against accidental outward movement but also cause the pilots and the blades to move together.

In carrying out the invention the rear portions of the blades 8 and the forward portions of the rear pilots 9 are provided with the notches 18 and 17 respectively for the reception of the inturned ends 19 of the individual leaf springs 20.

The rear portions of the pilots 9 are provided with notches 26 for the reception of

inturned terminal portions 28 of individual leaf springs 30.

The rear portions of the individual leaf springs 30 are inwardly offset and are provided with outwardly directed hooks 33 received in an internal groove 34 in the forward portion of an adjusting collar 35.

The individual leaf springs 30 are provided in advance of the hooks 33 with laterally extending shoulders 38 which ride over the body and thereby limit the inward movement of the leaf springs. The intermediate portions of the leaf springs are formed with depressions 36 to partly receive a connecting ring 37 by means of which the individual springs 30 are all held in an operative position.

In use the blades 8 and the pilots 7 and 9 are positioned in the gradually deepening grooves 6 and are connected by means of the several springs as clearly illustrated in Figure 1. The collar 35 is now adjusted longitudinally on the threaded rear portion of the reamer body to position the cutters and the pilots for making a cut of the desired diameter.

By simply adjusting the collar 35 on the reamer body the blades and pilots will simultaneously move. The particular connection between the blades and the pilots provides for accurate movement of the reamer and positively prevents one element from partaking of movement with respect to another element.

With reference to Figures 9, 10, 11 and 12, it will be observed that the relief or clearance 40 on the several blades 8 may be formed by positioning the blades within a circle somewhat smaller in diameter than the diameter of the hole it is intended to ream. The blades are circular ground and are subsequently moved outwardly to their normal cutting positions. The cutting edge of each blade will be on center or behind a line passing through center and all the blades will have the proper clearance.

The forward portion of each cutting blade is formed with a notch 42 of more or less triangular formation and being in one side of the blade. The side wall of the notch 42 co-operates with the circular ground clearance 40 in the formation of a more or less spiral lead 44. That is to say, by circular grinding the clearance on the blades the spiral leads will be formed at the same time and by the same operation. The lead thus formed is somewhat similar to the cutting edge of a left hand reamer and may be more expeditiously and economically formed than by present known methods of grinding. Of course any suitable angle may be employed in forming the leads by means of which the reamer is guided into the hole and enabled to cut the wall of the hole.

Particular attention is directed to the fact

that the ends of the blades and pilots have sharp corners which scrape the side and bottom walls of the grooves free of dirt and cuttings. This prevents the cuttings or dirt from lodging beneath the blades and pilots. 70

Having thus described the invention, what is claimed is:

1. A reamer comprising a body having a plurality of grooves, blades positioned in the grooves, separate pilots positioned in the same grooves which receive the blades, leaf springs having their terminal portions engaged with the blades and pilots, and an endless ring engaged with said springs to hold the same in engagement with said blades and said pilots. 80

2. A reamer comprising a body having grooves, aligned separate work engaging members positioned in the grooves and having their ends formed with notches, individual leaf springs having their terminal portions received in said notches and having their intermediate portions formed with depressions, and endless rings surrounding the reamer body and said leaf springs and received in said depressions. 90

3. A reamer comprising a body having grooves, aligned work engaging members positioned in the grooves and having notches, individual leaf springs having their terminal portions received in said notches and having their intermediate portions formed with depressions, and endless rings surrounding the reamer body and said leaf springs and received in said depressions, certain of said individual leaf springs having laterally projecting shoulders riding on the surface of said body. 100

4. A reamer comprising a body having grooves, aligned work engaging members positioned in the grooves, and having notches, individual leaf springs having terminal portions connected to said work engaging members and rings surrounding the reamer body and said leaf springs, certain of said individual leaf springs having laterally projecting shoulders riding over the surface of said body, and a collar adjustable on said body and having connection with said springs, whereby the adjustment of said collar on said body results in the simultaneous longitudinal and radial movement of all of said work engaging members and the springs associated therewith. 115

5. A reamer comprising a body, aligned working engaging members movable longitudinally of the body, the end portions of said work engaging members being provided with notches, leaf springs having their terminal portions hooked and received in said notches, the intermediate portions of said leaf springs being formed with depressions, rings surrounding the leaf springs and received in said depressions, said springs forming a mean for holding said work en- 120

gaging members in position, and means associated with certain of said leaf springs for moving the work engaging members and the leaf springs longitudinally of the body together.

6. A reamer comprising a body, work engaging members movable longitudinally and radially with respect to the body and having notches, separate leaf springs having hooks received in said notches, portions of said springs being formed with laterally extending shoulders slidably contacting with the surface of the body, and rings engaged with said springs to hold the work engaging members in position.

7. A reamer comprising a body, work engaging members associated with the body and having notches, individual leaf springs having hooks received in said notches, said springs being formed with laterally extending shoulders riding on the surface of the body to hold the springs in place, and rings engaged with said springs to tension the same and to hold the work engaging members in position, said leaf springs being provided with means to hold the ring against sliding movement on the springs.

8. A reamer comprising a body having grooves, work engaging members received in said grooves and having notches, leaf springs having their end portions hooked and received in said notches, said leaf springs being formed with depressions, and means received in said depressions for tensioning the springs and for holding the same in position partly in said grooves, the ends of said depressions forming stops to hold said means in place.

9. A reamer comprising a body having grooves, work engaging members in said grooves, leaf springs partly received in said grooves and held against lateral movement by the side walls of said grooves and having terminal portions engaged with said work engaging members, said leaf springs having outwardly directed hooks, and an adjusting collar having an internal groove receiving said outwardly directed hooks.

10. A reamer comprising a body having grooves, work engaging members in said

grooves, leaf springs partly received in said grooves and held against lateral movement by the side walls of said grooves and being engaged with said work engaging members, said leaf springs having outwardly directed hooks, an adjusting collar having an internal groove receiving said outwardly directed hooks, and a tensioning ring engaging said springs and holding the same in position.

11. A reamer comprising a body having grooves, work engaging members in said grooves, individual springs connected to said work engaging members, an adjusting collar on said body and having connection with said individual springs whereby the work engaging members are movable with said collar, and a ring surrounding said body and engaged with said springs.

12. A reamer comprising a body having grooves, work engaging members in said grooves, springs connected to said work engaging members, an adjusting collar having connection with said springs, and a ring engaged with said springs, the intermediate portions of said springs being provided with means limiting the movement of said ring longitudinally of said springs.

13. The construction set forth in claim 11, said springs being provided with laterally projecting shoulders riding on the surface of said body to limit the inward movement of the springs.

14. A reamer comprising a body having grooves, a plurality of aligned work engaging members in each of said grooves, separately formed springs detachably engaged at the ends thereof with said work engaging members, and means engaged with said individual springs to urge the springs into pressure engagement with said work engaging members.

15. A reamer comprising a body having grooves, a plurality of separate aligned work engaging members in each of said grooves, means connecting the work engaging members for movement together, and an adjusting device for simultaneously adjusting the aligned work engaging members.

In testimony whereof I affix my signature.
SAMUEL HARRY NORTON.
